UNITED STATES PATENT OFFICE.

PETER E. LITTLE, OF DAYTON, OHIO, ASSIGNOR TO THE STODDARD MANUFACTURING COMPANY, OF SAME PLACE.

HAY-TEDDER.

SPECIFICATION forming part of Letters Patent No. 393,115, dated November 20, 1888.

Application filed November 7, 1887. Serial No. 254,498. (No model.)

To all whom it may concern:

Be it known that I, PETER E. LITTLE, a citizen of the United States, residing at Dayton, in the county of Montgomery and State of Ohio, have invented certain new and useful Improvements in Hay-Tedders, of which the following is a full, clear, and exact description, reference being had to the accompanying drawings, forming part of this specification.

10 My invention relates to that class of hay-tedders known as "revolving tedders," in which the tedding-teeth are secured to a shaft revolved by the forward motion of the machine; and it has for its object the improvement of this class of machines, by which their construction is simplified and their efficiency increased.

15 The novelty of my invention will be herein set forth, and specifically pointed out in the claims.

In the accompanying drawings, Figure 1, Sheet 1, is a plan view of a tedder embodying my invention with a portion of the stripper-bar broken away. Fig. 2, Sheet 2, is an enlarged perspective of one of the tooth-holders. Fig. 3, Sheet 2, is a side elevation of the machine. Fig. 4, Sheet 2, is a sectional side elevation through the dotted line $x x$ of Fig. 1.

The same letters of reference are used to indicate identical parts in all the figures.

The main frame of the machine, supported and hung on the axle, may be of the usual or any suitable construction. In this instance it is composed of the side bars, A, forward cross-bars, B, and center bar, C, secured to the cross-bars. The carrying-wheels D are journaled upon the axle E, which in turn is suitably journaled in boxes F, secured to the bars A. The tedding shaft G is journaled in boxes H upon the rear ends of the bars A, and just outside of said bars is provided with sprocket-wheels I, suitably keyed or secured thereto. Drive-chains J connect the sprocket-wheels I with other sprocket-wheels, K, secured to the 45 axle E between the bars A and the carrying-wheels D.

The thill-frame is composed of the thills L, pivoted at their rear ends to the bars A, as at a, and the cross-bars M, to which the seat-beam N, carrying the seat O, is secured in the usual or any suitable manner.

To enable the main frame to be tilted to ad-

just the height of the tedding-teeth from the ground for various kinds or conditions of work, and to lock the main frame (when adjusted) and the thill-frame together, I employ a bell-crank locking hand-lever, P, which is pivoted to a segment-rack, Q, supported upon and secured to the cross-bars M. A pivoted link, R, connects the forward end of the bell-crank lever P to the forward-projecting end of the center bar, C, as seen more particularly in Fig. 4. The hand-lever is provided with the usual or any suitable latch, b, and operating-handle c, for holding the lever P locked to the rack Q in any of its adjusted positions.

The wheels D may have the usual ratchet-and-pawl connection with the axle E, so that in backing the machine the axle, and consequently the tedding shaft and teeth, will not 70 be revolved; or, if desired, the ratchet-and-pawl connection may be between the sprocket-wheels I and the tedding-shaft, to prevent the action of the tedding mechanism when the machine is backed, as will be readily understood.

The tedding-teeth S are of the general shape and construction of rake-teeth, except that their outer or working ends, instead of curving forward like rake-teeth, are given a reverse 80 or backward curve in the direction of their revolution, as shown. This is an important feature of my invention, for by thus shaping the teeth the tedding action is rendered more perfect, and the liability of the hay being carried up on the teeth is lessened.

The teeth are secured to the shaft G in sets, each set composed of two pairs, in the following manner: For every set of teeth there is a tooth-holder, T, Fig. 2, consisting of a sleeve 90 provided with tangential projections d, extending therefrom at points diametrically opposite, and provided on each side with outwardly-diverging gutters to receive the ends of each pair of teeth, which are bent to conform to the 95 shape of the gutters and are held securely by clips e, bolted to the holder, one of said clips on each side embracing the inner ends of the teeth and the other embracing the teeth at a point where they leave the holder. The holders, 100 with the teeth attached, are strung upon the shaft G, and after being properly spaced and adjusted are secured thereto by any suitable means. It will be seen that the teeth lie in

the grooves in the tooth-holders and are securely clamped at two points, all twisting or lateral motion being prevented by the bends in the teeth between the two clips, located, as before stated, one on each of the tangential projections. It will also be observed that the teeth of each pair diverge from each other, for a purpose to be presently explained. I prefer that the adjustment of the teeth be such as to

10 bring the sets spirally upon the shaft, as illustrated in the drawings, thereby lightening the draft of the machine when working.

To prevent the possibility of the grass or hay adhering to the teeth, I provide stripper-teeth 15 U, which are secured at their upper ends to a bar, V, which is supported upon the ends of inclined rails W, secured at their forward ends to the bars A of the main frame. The stripper-teeth are arranged in pairs coincident with 20 the sets of tedding-teeth, and the teeth of each pair diverge from each other and are curved forward at their lower ends in such manner that in the revolution of the tedding-teeth each pair as it ascends enters at the narrow or converging base between the separated ends of 25 the co-operating pair of stripping-teeth, and as the teeth continue to revolve they bear against the stripping-teeth throughout their entire length and effectually scrape off and remove any adhering material. It is obvious 30 that this result would be accomplished were either the tedder-teeth or the stripper-teeth alone diverging. For instance, were the stripper-teeth straight and the tedder-teeth diverging, 35 they would enter between the stripper-teeth at or near their bases, where they are close together; and, on the other hand, were the tedder-teeth straight and the stripper-teeth diverging, the ends of the latter would 40 be separated wide enough to pass outside the tedder-teeth, as will be readily understood. By this arrangement it is only necessary to employ one pair of stripper-teeth to two pairs of tedding-teeth, as the pairs on opposite sides 45 of the shaft rotate in the same plane.

From the above description it will be seen that I have produced a tedder of cheap and highly-efficient form, which by reason of the pairs of diverging teeth will cover a large surface, while affording the most secure and least number of fastenings for the teeth, and at the same time effectually preventing the retention of any hay or other material on the teeth.

Having thus fully described my invention, I 55 claim—

1. In a hay-tedder, the combination, with the tedding-shaft, of the tooth-holders carried thereby, having the tangential projections on opposite sides, with the diverging grooves 60 therein for the ends of the teeth, and clamps for holding the teeth in position, substantially as described.

2. In a hay-tedder, the combination, with the tedding-teeth arranged in pairs on a revolving tedding-shaft, the teeth of each pair diverging from each other, of coincident pairs 65 of diverging stripper-teeth, the ends of which

pass outside the tedding-teeth at their bases, or at a point where said tedding-teeth are near together, substantially as described.

3. In a hay-tedder, the combination, with the tedding-teeth arranged in pairs, the teeth of each pair diverging from each other, of tooth-holders mounted on a rotating tedding-shaft, each holding two pairs of tedding-teeth, 75 one on each side of the shaft, and coincident pairs of diverging stripper-teeth, the ends of which pass outside the tedding-teeth at their bases, or at a point where they are close together, and each pair of which engages two 80 pair of oppositely-arranged tedding-teeth, substantially as described.

4. In a hay-tedder, the combination, with the shaft, of a tooth-holder formed with the sleeve encircling the shaft, and with the 85 oppositely-arranged tangential projections grooved on both sides, and clamps or locking-clips for holding the teeth on each side of said projections, substantially as described.

5. In a hay-tedder, the combination, with a 90 revolving tedding-shaft and a set of tedding-teeth composed of two pairs of teeth, of a tooth-holder secured to said shaft and consisting of a sleeve provided with diametrically-opposite tangential grooved projections, each holding 95 a pair of tedding-teeth, with locking-clips for securing said teeth in the grooves, substantially as described.

6. In a hay-tedder, the combination, with each set of teeth composed of diametrically-roc arranged opposite pairs of diverging teeth, of a tooth-holder secured to the revolving tedding-shaft and consisting of a sleeve provided with diametrically-opposite tangential grooved projections, each adapted to hold a 105 pair of tedding-teeth, with clips for locking the teeth in the grooves, substantially as described.

7. In a hay-tedder, the combination, with the tedding-teeth bent in the form of a reverse 110 curve, with their working ends curved in the direction of their revolution, of a series of tooth-holders secured to the revolving tedding-shaft, and each consisting of a sleeve provided with diametrically-opposite tangential 115 grooved projections, each adapted to hold a pair of tedding-teeth, with clips for locking the teeth in the grooves, substantially as described.

8. In a hay-tedder, the combination, with 120 diametrically-opposite pairs of tedding-teeth bent in the form of a reverse curve, with their working ends curved in the direction of their revolution, of a series of tooth-holders secured to the revolving tedding-shaft, one for each 125 two pairs of teeth, and each consisting of a sleeve provided with diametrically-opposite tangential projections grooved on both sides, with clips for locking the teeth in the grooves, substantially as described.
